UNITED STATES PATENT OFFICE.

JAMES C. DORR, OF DANSVILLE, NEW YORK.

PROCESS OF MAKING MEDICATED TAMPONS.

961,689.

Specification of Letters Patent. Patented June 14, 1910.

Application filed January 30, 1909. Serial No. 475,190.

To all whom it may concern:

Be it known that I, JAMES C. DORR, a citizen of the United States, residing at Dansville, in the county of Livingston and 5 State of New York, have invented certain new and useful Improvements in Processes of Making Medicated Tampons, of which the following is a specification, reference being had therein to the accompanying 10 drawing.

This invention relates to an improved method of making pessary tampons, and has for its object to provide an improved process, as hereinafter set forth and claimed.

15 The principal object of the invention is to provide a device of the character described which will be of the proper anatomical shape and adapted to properly distribute suitable medicament, and which may 20 be readily removed from its medicament distributing position.

With the above and many other objects in view, the invention contemplates a pessary tampon which is formed of absorbent 25 fibers saturated with a medicament, said tampon being formed by pressing or molding the saturated fibers so that the ends thereof will radiate from the center and provided with a cord or its equivalent by 30 means of which the device may be removed, said cord also serving to retain additional tampon material or packing in place when necessary or desirable.

The invention will be fully understood 35 by reference to the accompanying drawings wherein the various steps in the improved process have been shown.

In said drawings—Figure 1 represents a 40 plurality of fibers bundled in lengths and having a looped cord attached to the center. Fig. 2 is a plan view of a mold showing the bundled fibers therein with the ends radiating from the center. Fig. 3 is a vertical central sectional view of a pressing mold, showing 45 the fibers therein with the looped cord projecting through the bottom of the mold. Fig. 4 is a perspective view of the finished tampon. Fig. 5 is a similar view, showing the looped cord serving to hold additional 50 tampon material or packing.

Referring to said drawings by numerals, 1 designates the bundled absorbent fibers, preferably wool, which are held in longitudinal lengths by means of the cord 2 which is 55 tightly wound and tied about the central portion of the bundle to compress the same,

said cord being of considerable length and looped at its end. When in the described bundled and centrally compressed condition, the fibers are immersed in a bath of heated 60 glycerin and gelatin to which the desired medicament is added, to thoroughly saturate the fibers, after which the fibers are straightened. The medicament used is such as will become semi-solid and elastic when cooling. 65

After the fibers have been thoroughly saturated with the medicament, they are placed in a mold, such as 3 having an opening formed through its bottom through which the looped cord is extended, see Fig. 3. 70 The fibers are arranged in the mold so that their ends will radiate toward the periphery of the mold, see Fig. 2, and the upper section 4 of the mold is adjusted upon the fibers and pressure applied thereto and retained until 75 the desired cup or other shape has been imparted to the fibers, after which the same is removed from the mold and allowed to dry, and harden.

To facilitate the placing of the bundled 80 fibers in the mold a hook 5 is employed for engaging with the loop of the cord 2, said hook being first passed through the hole in the bottom of the mold to draw the cord through and also to pull the fibers down 85 snugly into the mold.

After placing the fibers in the mold, and before applying pressure thereto, more of the medicament may be poured onto the 90 fibers so as to apply a lining or coating of medicament thereto, the surplus medicament being, of course, forced out of the mold through the bottom opening therein.

In Fig. 4 of the accompanying drawings 95 an example of the finished product is shown, in this instance, for illustrative purposes being shown cup-shaped, although it will of course be understood that the same is not limited to such shape.

In Fig. 5 the looped cord has been shown 100 as holding additional tampon or packing material in place, the same being designated by the numeral 6. This packing may be advisable for retaining the tampon in position and also for drainage purposes.

105 It will be seen from the foregoing description that the tampon is one that will retain its shape until all the medicament has been dissolved from its fibers, and it will also be seen that through the arrangement of the fibers so that they radiate from the center of the device, the medicament will be thor- 110

oughly distributed by capillary attraction to the organs requiring such medicament.

I claim as my invention:—

1. The process of making tampons which 5 consists in forming a bundle of wool fibers in longitudinal lengths, compressing the same centrally between its ends by means of a cord wound tightly and tied about the central portion of the bundle to compress the 10 same, said cord having a looped portion extending therefrom, saturating the bundle in a hot medicament, and then pressing the bundle into a cup-shaped form with the ends of the fibers forming the rim of the cup-shaped form.

15 2. The process of making tampons which consists in forming a bundle of absorbent

fibers in lengths, compressing the bundle centrally by a cord tied about the same, and having an extended looped end, saturating 20 the bundle in a bath of heated medicament, straightening the fibers, applying more medicament to the bundle of fibers to form a coating thereon, and pressing the bundle in a mold to form a cup-shaped receptacle with 25 the ends of the fibers forming the rim of the receptacle.

In testimony whereof I hereunto affix my signature in presence of two witnesses.

JAMES C. DORR.
